SIGHT FEED

Walter H. Kniskern, Prince George County, Va.,
assignor to Atmospheric Nitrogen Corporation,
New York, N. Y., a corporation of New York

Application March 5, 1931, Serial No. 520,323

6 Claims. (Cl. 184—96)

This invention relates to sight feeds of the general type in which a glass sight associated with a sight feed chamber is utilized to permit observation of the flow of drops of oil through a body 5 of heavy colorless liquid maintained within such sight feed chamber.

Sight feeds of the type to which the present invention is directed, usually comprise a sight feed chamber adapted to contain a heavy colorless liquid, a valved oil inlet and a valved oil outlet, an oil drop-forming nipple immediately associated with the oil inlet, together with some means including a glass tube or a glass disk permitting ready observation of the upward passage of successive drops of oil through the heavy liquid in the chamber. As is known in the art, measured quantities of oil are continuously or intermittently injected into the sight feed chamber through the valved oil inlet thereof by any suitable force feed lubricator. The oil thus fed into the chamber rises upwardly through the heavy liquid therein, and finally passes out of the chamber through the oil outlet, whence the oil is conducted through tubing to the part or parts 20 of the mechanism to be lubricated. During the operation of such sight feed devices, small quantities of the heavy colorless liquid in the sight feed chamber are from time to time carried out of the chamber along with the oil discharged through the outlet. Over a given period, the supply of heavy liquid in the sight feed chamber becomes gradually diminished, and ultimately it becomes necessary to introduce fresh liquid into the chamber to replenish the supply therein.

According to the construction of prior devices, it has been necessary, when it is desired to replenish the supply of heavy liquid in the sight feed chamber, to shut down the force feed lubricator altogether, and in most instances partially 40 disassemble the sight feed device in order to obtain access to the interior thereof to introduce the required additional quantity of heavy liquid into the sight feed chamber. The result has been that during the operation of replenishing the 45 liquid in the sight feed chamber, the oil supply to the mechanism being lubricated has been cut off completely. Such a shut down and cutting off of the oil supply to the moving mechanism is highly undesirable, particularly where the 50 sight feed is being used in connection with some continuously operating heavy duty machine or engine.

The principal object of the present invention is to provide a simple construction to facilitate 55 the replenishing of the supply of heavy liquid in

a sight feed chamber without shutting down the force feed pump, and while maintaining the continuous passage of such quantities of oil through the sight feed chamber as are usually required by the machine being lubricated.

Briefly considered, the invention comprehends a sight feed device including a sight feed chamber having an oil inlet and an oil outlet along with a glass sight for observing the passage of oil through the chamber, and an auxiliary valve-controlled duct or passage opening into the chamber having associated therewith a second valve-controlled conduit, through which conduit and auxiliary duct, on opening of the valve controlling the auxiliary duct, heavy liquid may be 10 injected into the sight feed chamber without interfering in any manner with the normal operation of the sight feed and the continuous passage of oil therethrough. The invention further comprises specific features of construction, 20 combination of elements, and arrangement of parts which are exemplified in the construction hereinafter set forth.

For a fuller understanding of the nature and objects of the invention, reference may be had 25 to the following detailed description taken in connection with the accompanying drawing in which:

Figure 1 is a vertical section of one form of sight feed device embodying the invention; 30

Fig. 2 is a vertical section of a modified form;

Fig. 3 is a vertical section through a combined top bolt and valve body forming a part of the sight feed shown in Fig. 2;

Fig. 4 is a horizontal section on line 4—4 of 35 Fig. 3;

Fig. 5 is a vertical section through the valve stem constituting one part of the embodiment of the invention illustrated in Fig. 2, and—

Fig. 6 is an elevation, on a reduced scale, of 40 the lower end of the body of the sight feed illustrated in Fig. 1 taken at right angles to the section shown in Fig. 1.

Referring to the drawing, and to Figs. 1 and 6 in particular, the reference numeral 10 indicates 45 the body of the sight feed. The general form of the body is cylindrical except for valves and inlet passages for the introduction of heavy fluid located in a projection cast integrally with the upper end of the body and which will hereafter 50 be described in more detail. The lower end of the body 10 is provided with two horizontally extending lugs 11 providing means for attaching the sight feed to the top of a reservoir, not shown, which contains oil and houses the pump units. 55

Directly beneath the center of the body 10, there is mounted an oil feed pump, not shown, the discharge passage of which communicates through oil inlet passage 12 and check valve 13 with the drop-forming nipple 14. The construction of the inlet check valve 13 and drop-forming nipple 14 is according to standard design and is well known in the art. Windows 15 are provided in opposite sides of the body 10, to facilitate observation of the passage of oil upwardly through the sight feed chamber.

The sight feed chamber indicated generally by the reference numeral 16, is formed by the base of body 10, the glass tube 17, the interior portion 15 of member 18 and the under side of top bolt 19. The glass tube 17 has its lower end set into an annular channel cut in the upper face of the lower part of body 10, and the upper end of tube 17 fits into an annular groove 20 formed between body 10 and ring 21. Ring 21, which is threaded inside the upper portion of body 10, when screwed down, exerts pressure on suitable gaskets 22, thus preventing leakage of oil from the chamber. Into the top portion of body 10 there is screwed the externally threaded member 18, and the joint between the body 10 and member 18 is made fluid-tight by gasket 23.

The reference numeral 31 indicates the oil outlet for the sight feed chamber. The outlet 31 passes axially through a discharge fitting 32, one end of which is shaped to provide a cylindrical section 33 adapted to receive the downwardly projecting shank 34 of the bolt 19. The outlet end of the fitting 32 may be provided with any desirable means for attaching thereto a pipe or tube for conducting the oil from the outlet passage 31 to the point or points on the machine at which the oil is to be employed for lubricating purposes. The outlet fitting or connection 32 has therein an outlet check valve 35 similar to the inlet check valve 13 arranged, however, in the reverse manner so that oil may only pass outwardly through the connection 32.

The lower end of the shank 34 of the bolt 19 is threaded to fit into the internally threaded upper end of the member 18 as indicated at 36. Leakage between the bolt and member 18, and the upper and lower surfaces of the sleeve section 33 is prevented by suitable gaskets 37. From the drawing it will be apparent that when the bolt 19 is screwed down tightly in place, the discharge fitting 32 is held firmly in the position shown.

The bolt 19 includes a short axial duct 40 opening at its lower end into the upper end of the sight feed chamber and terminating at its upper end in the transverse passage 41. At either end, the passage 41 opens into a circumferential groove 42 cut in the face of the shank 34 of the bolt. As is apparent from the drawing, the channel 42, when the parts are assembled in position, forms with the inner surface of the sleeve 33, an annular channel which, for all radial positions of the bolt 23, affords a connection between the sight feed chamber 16 and the outlet passage 31 in the discharge fitting 32.

Cast integrally with the upper portion of body 10 there is a projection indicated generally by the reference numeral 44, and containing auxiliary passages for the introduction of a heavy fluid into sight feed chamber 16, together with stop and check valves required for controlling the flow in the auxiliary passages. The projection 44 comprises primarily an auxiliary passage 45, communicating with the interior of the chamber be-

tween the ring 21 and the lower end of the member 18, and an inlet conduit 46 which may be connected to the auxiliary passage 45 by suitable manipulation of the conical pointed valve stem 47.

The lower end of the valve stem 48 is threaded to fit into the lower end of the branch 49 of the valve casing as indicated at 50. The packing gland 51 is similarly threaded into the upper end of the branch 49. The inlet conduit 46 passes axially through a second branch 54 of the projection 44. The nipple 55 is threaded into the branch 54 and is so formed as to receive the check valve 56 and its actuating spring which seats at its inner end against the valve casing 15 adjacent the conduit 46. A duct 57 in the inlet end of the nipple 55 forms a continuation of the inlet conduit 46. The outer end of the nipple 55 is externally threaded to facilitate connection 20 of the nipple to a suitable pipe or hose leading to a source of supply of heavy liquid.

In operation, oil passes from the pump, not shown, through inlet passage 12, past check valve 13, to drop-forming nipple 14. The drops rise through the heavy fluid contained in chamber 16 to the top interior portion of member 18 and pass through axial passage 40, transverse passage 41, channel 42, and axial passage 31, past check valve 35, and are lead by a pipe, not shown, connected to fitting 32, to the portion of the machine to be lubricated.

When, through long operation, the heavy fluid within the sight feed chamber 16 has become depleted and it is desired to replenish same, a pump not shown is connected to nipple 55, the valve stem 48 is rotated, which moves the conical point 47 away from seat 47'. The pump is then operated, forcing heavy fluid from the pump through passage 57, past check valve 56, through passage 46, into the annular chamber surrounding the conical point 47 of valve stem 48, thence through passage 45 into chamber 16. When sufficient heavy fluid has been forced into chamber 16, the pump is removed, escape of heavy fluid being prevented by check valve 56, and stem 48 is screwed down so that conical point 47 engages with seat 47', thus closing the passage through which the heavy fluid might escape from chamber 16 in case check valve 39 should leak.

In the embodiment of the invention illustrated in Fig. 2, the construction of the body 60 is the same as that of body 10 described in connection with Fig. 1 except that the body 60 is not provided with an integral projection similar to projection 44 accommodating the check and stop valves and associated passages. In Fig. 2, the oil inlet passage, the inlet check valve and the drop forming nipple for the sight feed chamber 61, together with the member 18 and the outlet fitting or connection are of the same construction and arrangement as in the embodiment of the invention shown in Fig. 1, and are designated by like reference characters. However, in the modification of Fig. 2, the liquid supply in the sight feed chamber 61 is replenished by means of a valve directly above the chamber rather than at the side as in Fig. 1.

The valve body or bolt 66 is shown assembled with the associated parts in Fig. 2 and in section in Fig. 3. The auxiliary passage 71 extends axially through the shank 72 projecting downwardly from the valve body. The upper end of the auxiliary passage 71 is adapted to form a seat for the conical valve 73, and when the valve is open; the auxiliary passage 71 affords a connec-

tion between the sight feed chamber 61 and a chamber 74 formed by the underside of the valve stem 75 and the lower end of the internally threaded chamber 76 of the valve body. The valve stem 75, shown in section in Fig. 5 has there-in a longitudinal inlet conduit 78 opening at its lower end into a short transverse passage 79. The upper end of the valve stem 75 is externally threaded to receive a valved inlet nipple indicated on the drawing by the reference numeral 80. Leakage around the valve stem 75 is prevented by suitable packing 81 held in place by the gland 82 and the gland nut 83 threaded to screw down over the head of the externally threaded upper end of the valve body 66. The valve 73 may be manipulated by means of a collar 84 fixed to the valve stem by studs 85.

Cut into the shank 72 of the valve casing 66 is an annular groove 86 which, when the parts are assembled, forms with the interior wall of the cylindrical end portion of the discharge fitting 32 an annular channel 87 communicating with the outlet passage 31 in the discharge fitting or connection 32. As shown in Figs. 3 and 4, the lower end of the shank 72 is longitudinally grooved or channelled as at 88 and 90 to provide communication between the annular channel 87 and the upper end of the sight feed chamber 61. Tube 91 is pressed into a counter-bore 92 in the lower end of the shank 72 to effect an extension for the auxiliary passage 71 into the middle portion of the chamber 61. By reason of this construction, liquid injected into the sight feed chamber through the auxiliary passage 71 is fed substantially into the center section of the sight chamber 61.

In the operation of the sight feed of Fig. 2, oil passes from the pump, not shown, through inlet passage 12, past check valve 13, to drop-forming nipple 14. The drops rise through the heavy liquid contained in chamber 61, to the top interior portion of member 18, and pass through the grooves 88 and 90, channel 87, and passage 31, past a check valve and are lead by a pipe not shown, connected to fitting 32, to the portion of the machine to be lubricated.

When, through long operation, the heavy liquid within the sight feed chamber 61 has become depleted and it is desired to replenish same, a pump not shown, is connected to the screw threads at the top of the fitting 80, the valve stem 75 is rotated by means of collar 84, which moves the conical point 73 away from seat 73'. The pump is then operated, forcing heavy liquid from the pump past the check valve in nipple 80, through axial passage 78, transverse intersecting passage 79, into the annular chamber 74 surrounding the conical valve 73, through axial passage 71 and extension tube 91 into chamber 61. When sufficient heavy fluid has been forced into chamber 61, the pump is removed, escape of heavy fluid being prevented by the check valve in nipple 80, and stem 75 is screwed down so that conical valve 73 engages with seat 73', thus closing the passages through which the heavy fluid might escape from chamber 61, in case the check valve should leak. It will thus be seen that the introduction of the necessary amount of heavy fluid may be accomplished without in any way interfering with the continuous passage of oil through the sight feed chamber from the nipple 14 to the outlet 31.

As previously mentioned, during the operation of sight feeds of the type contemplated by the present invention, small quantities of the heavy colorless liquid maintained in the sight feed

chamber are from time to time carried out of the chamber along with the oil leaving through the outlet. Thus, over a more or less extended period, the supply of liquid in the sight feed chamber becomes gradually diminished and ultimately, it 5 has been necessary in prior devices, to shut down the force feed pump and partially disassemble the sight feed in order to replenish the supply of liquid in the sight feed chamber. Such a shut-down is obviously undesirable, particularly 10 where the sight feed is being used in connection with a continuously operating mechanism. According to the present invention, the supply of liquid in sight feed chamber may be replenished without stopping the force feed oil pump and 15 while maintaining the continuous passage of oil through the sight feed chamber in such quantities usually required by the machine being oiled.

It will be observed in both embodiments of the invention illustrated that the passages through 20 which the heavy fluid, such as a glycerine-water mixture, enters the chambers are located considerably below the top of the chamber. In Figure 1 passage 45 through which the heavy fluid enters chamber 16 is located just above ring 21, while 25 chamber 16 extends up inside member 18 and the lower conical portion of top bolt 19. In Figure 2 the heavy fluid is introduced into chamber 61 through tube 91, which terminates at substantially the bottom of ring 21. In both em- 30 bodiments of the invention the heavy fluid is introduced below the top of the chamber, in order to insure that when a certain volume of heavy fluid is pumped into the chambers with the expulsion of a corresponding quantity from the 35 chamber through the outlet passages provided for the escape of oil, that the liquid expelled will be oil and not heavy fluid, which might be the case if the heavy fluid were introduced near the outlet passage provided for oil. 40

The invention may be employed in connection with sight feeds of construction other than those shown in the drawing; for example, the glass tube 17 may obviously be replaced by a metallic casing provided with suitable glass windows of 45 the type commonly referred to as "bull's eyes". Since certain changes may be made in the above constructions and different embodiments of the invention may be made without departing from the scope thereof, it is intended that all matters 50 contained in the above description or shown in the accompanying drawing shall be considered as illustrative and not by way of limitation. 55

I claim:

1. A sight feed comprising a sight feed chamber adapted to contain a heavy liquid, the said chamber having a sight glass associated therewith, an oil inlet at the lower end of the chamber, an oil outlet at the upper end of the chamber, a valve casing associated with and forming 60 a part of the chamber, the valve casing having therein an auxiliary passage communicating with the chamber, a valve for controlling the flow of liquid through the auxiliary passage, an inlet conduit in the stem of the said valve, said inlet 65 conduit being adapted when the valve is open to be in communication with the auxiliary passage, and a valve in the inlet conduit for controlling the passage of liquid therethrough.

2. A sight feed comprising a sight feed chamber adapted to contain a heavy liquid, the said chamber having a sight glass associated therewith, an oil inlet at the lower end of the chamber, an oil outlet for the chamber, a valve casing having a shank forming one end of the chamber, 75

- 5 a channel through the shank connecting the chamber with the oil outlet, an auxiliary passage in the valve casing passing thru the shank and communicating with the chamber, a valve for controlling the flow of liquid through the auxiliary passage, an inlet conduit in the stem of the said valve, means for connecting the inlet conduit and the auxiliary passage, and a valve in the inlet conduit for controlling the passage of liquid therethrough.
- 10 3. A sight feed comprising a sight feed chamber adapted to contain a heavy liquid, the said chamber having a sight glass associated therewith, an oil inlet at the lower end of the chamber, an oil outlet for the chamber, a valve casing having a shank forming one end of the chamber, a channel through the shank connecting the chamber with the oil outlet, an auxiliary passage in the valve casing passing thru the shank and communicating with the chamber, a tube connected to the auxiliary passage and projecting into an intermediate section of the chamber, a valve for controlling the passage of liquid through the auxiliary passage, an inlet conduit in the stem 15 of the valve disposed axially to the auxiliary passage, means for connecting the inlet conduit and the auxiliary passage, and a valve in the inlet conduit for controlling the passage of liquid therethrough.
- 20 4. A sight feed comprising a body portion having a sight opening in the side wall thereof, means forming a sight feed chamber adapted to contain a heavy liquid including the base of said body portion, a sight feed tube in said body portion and having one end abutting said base, and a hollow member detachably connected to and constituting an extension of said body portion; a valve-controlled inlet passage in said base, a fitting having a valve-controlled outlet passage communicating at one end with said sight feed chamber, means—including a bolt forming one end of the sight feed chamber and affording communication between the sight feed chamber and the passage in the fitting—for connecting said fitting and said hollow member in leakproof relation, a valve-controlled auxiliary passage opening into said chamber for introducing heavy liquid into said chamber, and a valve-controlled inlet communicating with the auxiliary passage.
- 25 5. A sight feed comprising a body portion having a sight opening in the side wall thereof, means forming a sight feed chamber adapted to contain a heavy liquid including the base of said body portion, a sight feed tube in said body portion and having one end abutting said base, and a hollow member connected to and constituting an extension of said body portion; packing engaging the sight feed tube and said base, packing engaging the opposite end of the sight feed tube, an adjustable ring within said chamber formed to engage the inner surface of said body portion, and the packing engaging said opposite end of the sight feed tube, said ring being arranged on 30 adjustment to tighten packing to prevent leakage between the ends of the sight feed tube and the body portion, a valve-controlled inlet passage in said base, a fitting having a valve-controlled outlet passage communicating at one end with said sight feed chamber, means—including a bolt forming one end of the sight feed chamber and affording communication between the sight feed chamber and the passage in the fitting—for connecting said fitting and said hollow member in leakproof relation, a valve-controlled auxiliary passage opening into said chamber for introducing heavy liquid into said chamber, and a valve-controlled inlet communicating with the auxiliary passage.
- 35 6. A sight feed comprising a body portion having a sight opening in the side wall thereof, means forming a sight feed chamber adapted to contain a heavy liquid including the base of said body portion, a sight feed tube in said body portion and having one end abutting said base, and a hollow member connected to and constituting an extension of said body portion; packing engaging the sight feed tube and said base, packing engaging the opposite end of the sight feed tube, an adjustable ring within said chamber formed to engage the inner surface of said body portion and the packing engaging said opposite end of the sight feed tube, said ring being arranged on 40 adjustment to tighten packing to prevent leakage between the ends of the sight feed tube and the body portion, a valve-controlled inlet passage in said base, a fitting having a valve-controlled outlet passage communicating at one end with said sight feed chamber, means—including a bolt forming one end of the sight feed chamber and affording communication between the sight feed chamber and the passage in the fitting—for connecting said fitting and said hollow member in leakproof relation, a valve-controlled auxiliary passage opening into said chamber for introducing heavy liquid into said chamber, and a valve-controlled inlet communicating with the auxiliary passage.
- 45 5. A sight feed comprising a body portion having a sight opening in the side wall thereof, means forming a sight feed chamber adapted to contain a heavy liquid including the base of said body portion, a sight feed tube in said body portion and having one end abutting said base, and a hollow member connected to and constituting an extension of said body portion; packing engaging the sight feed tube and said base, packing engaging the opposite end of the sight feed tube, an adjustable ring within said chamber formed to engage the inner surface of said body portion and the packing engaging said opposite end of the sight feed tube, said ring being arranged on 50 adjustment to tighten packing to prevent leakage between the ends of the sight feed tube and the body portion, a valve-controlled inlet passage in said base, a fitting having a valve-controlled outlet passage communicating at one end with said sight feed chamber, means—including a bolt forming one end of the sight feed chamber and affording communication between the sight feed chamber and the passage in the fitting—for connecting said fitting and said hollow member in leakproof relation, a valve-controlled auxiliary passage opening into said chamber for introducing heavy liquid into said chamber, and a valve-controlled inlet communicating with the auxiliary passage.
- 55 5. A sight feed comprising a body portion having a sight opening in the side wall thereof, means forming a sight feed chamber adapted to contain a heavy liquid including the base of said body portion, a sight feed tube in said body portion and having one end abutting said base, and a hollow member connected to and constituting an extension of said body portion; packing engaging the sight feed tube and said base, packing engaging the opposite end of the sight feed tube, an adjustable ring within said chamber formed to engage the inner surface of said body portion and the packing engaging said opposite end of the sight feed tube, said ring being arranged on 60 adjustment to tighten packing to prevent leakage between the ends of the sight feed tube and the body portion, a valve-controlled inlet passage in said base, a fitting having a valve-controlled outlet passage communicating at one end with said sight feed chamber, means—including a bolt forming one end of the sight feed chamber and affording communication between the sight feed chamber and the passage in the fitting—for connecting said fitting and said hollow member in leakproof relation, a valve-controlled auxiliary passage opening into said chamber for introducing heavy liquid into said chamber, and a valve-controlled inlet communicating with the auxiliary passage.

WALTER H. KNISKERN.
